PHONOGRAPH TURNTABLE

David Barry Linford Brickwood, London, England, assignor to Strathearn Audio Limited, Belfast, Northern Ireland

Filed Nov. 27, 1974, Ser. No. 527,634

Claims priority, application Great Britain June 6, 1974

Term of patent 14 years

Int. Cl. D14—01

U.S. Cl. D56—4 R

Fig. 2.

FIG. 1 is a front, top and right side perspective view of a phonograph turntable showing my new design; and

FIG. 2 is a view similar to FIG. 1 with the lid in raised position.

The turntable based platform extends to the rear.
I claim:

The ornamental design for a phonograph turntable, as shown and described.
